C. F. STAPLES

WASHING MACHINE

Filed April 21, 1924

FIG. 6

Fig. 1

INVENTOR
Charles F. Staples
BY

ATTORNEY

UNITED STATES PATENT OFFICE.

CHARLES F. STAPLES, OF DETROIT, MICHIGAN.

WASHING MACHINE.

Application filed April 21, 1924. Serial No. 707,914.

My invention relates to improvements in washing machines, in which fabrics may be washed, rinsed, blued and dried with a minimum of labor, and the objects of my improvements are first, to provide a fabric-receiving tub or container in which fabric may be washed; second, to provide a perforated container in which fabric may be placed after washing and rotated for removing adherent water therefrom by centrifugal force, third, to provide a secondary container surrounding the bottom and side-walls of said perforated container for gathering the liquids thrown from said perforated container, fourth, to provide an outlet from said secondary casing for draining liquids from or admitting liquids to said secondary casing independent of said washing container, fifth, to provide a hose of sufficient length so that the tub may be filled or emptied without the use of other receptacles.

Generally speaking my invention may be defined as consisting of a centrifugal pump within a tub, a perforated container superimposing said tub, said pump and said container being so designed and proportioned as to rotate at the same speed as a standard electric motor, thus eliminating the use of gears, belts or other speed reductions.

I attain these objects by the mechanism illustrated in the accompanying drawing in which—

Figure 1 is a vertical section of the machine; Figure 2, a plan view of the machine as it appears after the removal of the cover.

Similar numerals refer to similar parts throughout the several views.

The washing tub 1, preferably made of metal and having a cylindrical side wall and flat bottom is supported on legs 6 by pins 19 at a convenient height. The rinsing tub 2 is supported over washing tub 1 by pump cover 7 and completely surrounds the bottom and side walls of perforated container 3. Pump rotor 18 is fastened to vertical shaft 8 by pin 22. Pump cover 7 is held in the central portion of the washing tub by screws 17 and is constituted by a cylindrical wall 24 thus forming a compartment which is enlarged at its lower portion 25 to enclose

the pump rotor 18. The cylindrical wall of the pump cover and the enlarged lower portion are provided with liquid passages 26, 27 respectively, for the passage of the cleaning fluid during the operation of the machine.

Perforated container 3 is rotated by friction washers 14 and 15 and washer 14 being driven by vertical shaft 8 and pin 23.

Motor 21 which drives vertical shaft 8 through pin 20 is held in position by bracket 10 and screws 16.

Rinsing tub drain 13 is threaded at its outer end to receive a standard hose and coupling 11 said hose and coupling 11 to be used for filling or emptying rinsing tub 2.

Standard hose and coupling 12 is for filling or emptying washing tub 1. Packing nut 9 is preferably made large enough to permit of tightening by hand. Washing tub cover 4 is removed by handles 5.

I am aware that prior to my invention laundry machines have been made with centrifugal driers and pumps, and while I have described my invention in detail and pointed out at length the construction and arrangements which my experiments now indicate to be most desirable, I do not limit myself to such details or arrangements except as the same may be included in the claims here-to annexed or may be rendered necessary by the prior state of the art.

Having thus described my invention, what I claim is:—

1. In a washing machine, a washing tub having an open top, a rinsing tub of smaller diameter than said washing tub disposed above and extending into said washing tub, a perforated basket disposed within said rinsing tub, a vertical, rotatably mounted shaft in said washing tub, said basket being mounted on said shaft.

2. In a washing machine, a washing tub having an open top, a compartment having a surrounding wall provided with openings therethrough and extending upwardly from the bottom of said washing tub, a rinsing tub extending into the open top of the washing tub and resting upon said compartment, a pump mounted on said shaft and located in said compartment, a perforated basket

within said rinsing tub and mounted on the upper end of the shaft, and means for rotating said shaft.

3. In a washing machine, a washing tub having an open top, a compartment having a surrounding wall provided with openings therethrough and extending upwardly from the bottom of the washing tub, a rinsing tub

supported within the open top of the washing tub, a shaft extending through said compartment, a pump mounted on said shaft and located in said compartment, a perforated basket within said rinsing tub and mounted on the upper end of said shaft, and means for rotating said shaft.

CHARLES F. STAPLES.
